UNITED STATES PATENT OFFICE

JONATHAN S. MAESDEN, OF EDGERTON, WISCONSIN

AUTOMATIC GARAGE DOOR OPENING AND CLOSING DEVICE

Application filed December 21, 1929. Serial No. 415,815.

This invention relates to means for opening and closing garage doors by a vehicle approaching and leaving the garage, so that it is unnecessary for the driver to leave his vehicle to open the doors when he wishes to place the vehicle in the garage or to close the doors when he is driving the vehicle from the garage.

The general object of the invention is to provide motor operated means for opening the doors, weights or the like for closing the doors, trip means for closing a switch in the motor circuit when a car approaches the garage so that the doors will be opened and means whereby the trip means will permit the weights to close the doors when a vehicle is leaving the garage.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:—

Figure 1 is a longitudinal sectional view through a garage equipped with the invention.

Figure 2 is a horizontal sectional view.

Figure 3 is a view of the train of gearing for operating the drum on which the cables which open the doors are wound, this view also showing the clutch means.

Figure 4 is a side view of Figure 3.

Figure 5 is a side view of the trip means.

Figure 6 is a front view thereof.

Figure 7 is a plan view thereof.

In these drawings, the letter A indicates a garage and the letter B indicates the doors thereof. These doors are normally held closed by the weights 1 connected with the doors by the cables 2 which pass over suitable guiding pulleys. A base 3 is fastened to one of the interior walls of the garage and carries a frame 4 in which is journaled the shafts 5, 6 and 7. These shafts are connected together by the train of gears 8 and a pulley

9 is connected with the shaft 5 over which passes a belt 10 which also passes over a pulley 11 fastened to the shaft of a motor 12 supported on the base. The circuit of the motor is controlled by a switch 13. Thus when the switch is closed, the motor will rotate the shaft 7 at a reduced speed through the reducing gears 8.

A drum 14 is rotatably arranged on the shaft 7 and has a clutch part 15 engaging a stationary clutch part 16 on the shaft, these clutch parts being normally held in engagement by a spring 17 on the shaft which tends to force the drum and its clutch part toward the clutch part 16. A clutch fork 18, pivoted to a part of the frame and engaging a groove 19 associated with the drum, acts to move the clutch parts into and out of engagement. Cables 20 are fastened to the drum and pass over suitable guiding pulleys 21 to the bell cranks 22 located adjacent the front of the garage at the top thereof, the long arm of each bell crank having rollers 23 at its free end which engage substantially rectangular shaped track members 24 fastened to the inner face of each door so that when the cables are wound on the drum, the bell cranks will be actuated to cause the rollers to exert pressure against the track members and thus open the doors and lift the weights. A cable 25 is connected with the short arm of one of the bell cranks and is also connected with the switch, this cable acting to move the switch to open position when the doors are opened so that the circuit of the motor is broken when the doors are opened.

Brackets 26 are arranged in front of the garage and form bearings for a shaft 27 on which are rotatably arranged the drums 28 and 29 and the collar 30 which is located between the drums and to which a trip arm 31 is connected. Angle shaped arms 32 are connected with the drums 28 and one of these arms extends in front of the trip arm 31 and the other in rear thereof. A cable 33 is connected with the bottom part of the drum 28 and a cable 34 is connected with the top part of the drum 29. The cable 33 passes over the guiding pulleys 35 and is connected to the switch and acts to close the switch when a car

approaching the garage strikes the lever 31, which causes said lever to move the arm 32 of the drum 28 and thus partly winds the cable 33 on the drum. The cable 34 passes over guiding pulleys 36 and is attached to the clutch fork so that when a car leaving the garage strikes the lever 31, said lever will move the drum 29 through its arm 32 and partly wind the cable 34 on the drum and thus cause the cable 34 to move the clutch lever to releasing position so that the weights can close the doors. A cable 37 is connected with the clutch fork and will, when pulled upon, cause the fork to move the clutch parts into engagement, this cable passing over the guiding pulleys 38, the front one of which is placed adjacent the point of connection of the cable with the front wall of the garage, this connecting point being shown at 39. A projection 40 on one of the doors will engage that part of the cable between the front pulley 38 and the connecting point 39 and thus exert a pull upon the cable to cause it to move the clutch parts to operative position.

From the foregoing it will be seen that the doors are normally held closed by the weights and when the doors are so closed, the cable 37 is engaged by the projection 40 and thus this cable will move the clutch fork to a position where the clutch parts are in operative position. Then when a vehicle approaches the front of the garage, it will strike the trip lever 31, moving the same forwardly, so that this lever, engaging the arm 32 of the drum 28, will exert a pull upon the cable 33 so that the switch of the motor will be closed by said cable and as the clutch parts are in operative position, the motor will rotate the drum and wind the cables 20 thereon so that these cables will cause the bell cranks 22 to swing the doors to open position. When the doors are opened, the cable 25 will raise the switch to open position so that the motor ceases to operate, but the drum, being connected with the gearing, cannot rotate, so that the doors remain open. The movement of the switch by the cable 25 will exert a pull on the cable 33, so that the trip mechanism is moved to neutral position. After the vehicle enters the garage, the driver moves the clutch fork 18 to release the drum from the stationary clutch and then the weights will close the doors and cause the cable 37 to return the clutch parts to operative position. When the vehicle is to leave the garage, the switch is closed so that the motor will operate the drum to cause the cables 20 to open the doors and as before stated, when the doors are opened, the cable 25 will move the switch to open position. Then when the vehicle is run out of the garage, it will strike the trip lever 31 so that said lever will rotate the drum 29 and partly wind the cable 34 thereon and this cable will move the clutch parts to releasing position so that the weights can close the doors and

as the doors close, the cable 37 will return the clutch parts to operative position so that the parts are set ready to be operated by a car approaching the doors to open the doors.

It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:—

1. In combination with a garage and a door, means for normally holding the door in closed position, motor driven means for opening the door, including a drum and clutch means therefor and a switch in the motor circuit, means operated by a vehicle approaching the door for closing the switch to cause the motor to open the door, means for opening the switch when the door reaches open position, manually operated means for releasing the clutch means to permit the door to close and means operated by a vehicle leaving the garage, including the means operated by a vehicle approaching the garage and the manually operated means for moving the clutch to inoperative position whereby the doors will close after the vehicle passes from the garage and means operated by the closing of the door for returning the clutch to operative position.

2. In combination with a garage and its door, a trip member in front of the door and operated by a vehicle entering and leaving the garage, means for normally holding the door in closed position, a drum, a motor for driving the same, a switch in the motor circuit, clutch means associated with the drum, a cable connected with the drum and with means associated with the door whereby the winding of the cable on the drum will open the door, means operated by a vehicle approaching the garage striking the trip for closing the switch whereby the door will be opened, means for opening the switch on the opening movement of the door, means operated by the trip when the same is operated by a vehicle leaving the garage for moving the clutch to releasing position so that the door can close and means operated by the closing of a door for moving the clutch to operative position.

3. In combination with a garage and its doors, a trip in front of the doors, means for normally holding the doors in closed position, a pair of bell cranks supported in the garage and each having one arm adapted to open and close a door, a drum, cables thereon connected with the bell cranks, a motor, reducing gears connecting the same with the drum, a clutch for connecting the drum to its shaft and disconnecting it therefrom, a switch in the motor circuit, means operated

by the trip when the same is moved by a vehicle approaching the garage to close the switch whereby the motor will operate the drum to open the doors, means for opening the switch when the doors reach open position, means operated by the trip when the same is moved by a vehicle leaving the garage for moving the clutch to releasing position whereby the doors will close and means operated by the closing of the doors for moving the clutch to operative position.

4. In combination with a garage and its doors, means for normally holding the doors in closed position, a track on each door, a bell crank pivoted in the garage and having rollers on one end thereof engaging the track whereby movements of the bell cranks will open the doors, a drum, cables connecting the drum with the other ends of the bell cranks, a shaft for the drum, clutch means for connecting the shaft with the drum and disengaging it from the drum, a motor, reducing gears connecting the same with the shaft, a circuit for the motor, a switch in the circuit, a trip member in front of the garage and consisting of two drums and a member arranged between the drums and carrying a lever, said drums having arms thereon, one extending in front of the lever and the other in rear of the lever, oppositely wound cables on the drums, one cable being connected with the switch and the other with the clutch whereby when a vehicle approaches the garage, the trip will be operated to close the switch and when a vehicle leaves the garage, the trip will be operated to release the clutch, a cable connecting one of the bell cranks with the switch whereby opening of the door will open the switch, another cable connected with the clutch and a projection on a door engaging a part of said cable when the door is closed to cause said cable to move the clutch to operative position.

In testimony whereof I affix my signature.

JONATHAN S. MARSDEN.
